Application November 7, 1946, Serial No. 708,353

10 Claims. (Cl. 198—20)

1

This invention relates to oven conveyors which transfer coated and lithographed sheets or the like for drying and other treatment and has particular reference to devices for releasing individual sheets from each of a plurality of wickets carried on a continuously moving conveyor.

An object of the invention is the provision in an oven conveyor for transferring coated and lithographed metal sheets supported in sheet carrying wickets, of a device for engaging and releasing an individual sheet relative to its supporting wicket.

Another object of the invention is the provision in an oven conveyor having sheet carrying wickets with supporting hooks for holding sheets being advanced along the lower run of the conveyor, of sheet lifting and sheet releasing devices located adjacent the conveyor run for raising each sheet clear of supporting wicket hooks and for effecting discharge of the individual sheet.

Another object of the invention is the provision in an oven conveyor of the character described of a supporting wicket device for engaging and for separating a single wicket from the following wickets without stopping movement of the conveyor preparatory to releasing the sheet from such a separated wicket.

A further object of the invention is the provision in such an oven conveyor of a sheet bowing device located adjacent conveyor chains and cooperating with a feed lifting device so that sheets, particularly wide sheets, will clear the wicket hooks easily during the separation preparatory to being discharged from the conveyor chains.

Numerous other objects and advantages of the invention will be apparent as it is better understood from the following description, which, taken in connection with the accompanying drawings, discloses a preferred embodiment thereof.

Referring to the drawings:

Figure 1 is a side elevation of one end portion of a can conveyor mechanism embodying the present invention, with parts broken away;

Fig. 2 is a vertical sectional view taken substantially along the line 2—2 in Fig. 1 and drawn to a slightly smaller scale;

Fig. 3 is a view similar to Fig. 1 drawn to a greatly enlarged scale and showing additional parts with some parts eliminated;

Figs. 4 and 5 are fragmentary views of certain of the sheet discharge mechanism illustrated in Fig. 3, these views showing different positions of the operating parts;

Fig. 6 is a vertical transverse sectional view taken substantially along the section line 6—6 in Fig. 4, parts being broken away; and

2

Fig. 7 is a plan sectional view taken substantially along the section line 7—7 in Fig. 4 with parts removed.

As a preferred embodiment of the invention the drawings illustrate portions of a conveyor for a drying oven of the character shown in United States Patent 1,468,181, issued September 18, 1923, to C. Wagner et al. In such an oven sheets A are transferred to an oven conveyor B (Fig. 1) from a suitable source of supply as from a coating or printing machine. The sheets are carried in an "on-edge" position in wicket hooks, the wicket and the hooks being a part of the conveyor system.

In the oven conveyor of the accompanying drawings there are two inner conveyor chains 11 (see also Fig. 2) mounted in horizontally spaced relation. These conveyor chains are carried over suitable chain sprockets 12, only the sprockets at

10 one end of the conveyor being shown. The two end sprockets shown are mounted on a conveyor shaft 13. This shaft is journaled in bearings 14 which may be secured to or formed integrally with side frames 15.

15 Two side frames 15 are shown, these being located at the sheet discharge end of the machine. Similar side frames may be used at the opposite end of the machine, these side frames forming only a portion of the supporting structure. The

20 two side frames shown are held together adjacent the bottom by a tie rod a (Figs. 1, 2 and 7), the ends of which are anchored in clamp plates b bolted to the side frames. Other transverse supports include a cross bar c bolted at its ends to the side frames. Each side frame also is braced by an intermediate bar d. A lower connecting tie frame e extends on each side between the side frames 15 and a second transverse cross bar f is carried on the tie frames e (Figs 4 and 5).

25 Other frame parts may be used for the necessary support of the working parts. It is believed a more detailed description of these structures is not necessary for purposes of the present invention.

30 Fig. 2 is a vertical sectional view taken substantially along the line 2—2 in Fig. 1 and drawn to a slightly smaller scale;

35 Fig. 3 is a view similar to Fig. 1 drawn to a greatly enlarged scale and showing additional parts with some parts eliminated;

40 Figs. 4 and 5 are fragmentary views of certain of the sheet discharge mechanism illustrated in Fig. 3, these views showing different positions of the operating parts;

45 Fig. 6 is a vertical transverse sectional view taken substantially along the section line 6—6 in Fig. 4, parts being broken away; and

50 Fig. 7 is a plan sectional view taken substantially along the section line 7—7 in Fig. 4 with parts removed.

outer edge of each wicket is formed with two spaced hooks 19 (see also Fig. 7) one hook element being located near each side of the machine.

Both the upper and the lower runs of the chain conveyors 11 ride along spaced bars or rails 20 which are carried by the frames 15 at the front and rear of the oven (Figs. 1, 2 and 3). The two rails 20 on each side are tied together by connecting straps 21. The conveyors carry 10 flanged supporting rollers 22 which ride directly on the rails as they rotate on suitable pins carried in the chains. This construction prevents the conveyor chains from sagging under the combined weight of the wickets and the 15 sheets. The outer looped end of each wicket 16 when passing along the lower run of the conveyor also is supported by spaced rails 24.

The rails 24 are suitably secured to the frames 15 the rails at the front resting on the cross bar c which extends between the side frames 15. The rails 24 are thus indirectly carried by the side frames both at the front and at the rear of the machine.

The wickets 16 are confined between the upper and lower rails 20 and 24 as they advance along the lower run of the conveyor chains 11. On both the upper and lower runs the conveyor wickets 16 are disposed in slightly inclined position so that the uncoated surface of each sheet faces away from its supporting wicket. The spaced rails 24 for the lower run cause a slight spacing between adjacent wickets. This assists in maintaining a more even movement of the wickets and maintains them in a better controlled position for discharge of the sheet, as will be explained hereinafter.

After treatment in the oven, the sheet A is ready for discharge. Such a sheet moving toward the left (Fig. 1) on the lower run of the conveyor passes between the side frames 15 at the front ends of the rails 20 and 24. A wicket separating device C (Fig. 3) is the first of a series of mechanisms to operate incident to discharging the sheet from its supporting wicket 16 at this position.

The wicket separating device C is in two sections, one for each side of the sheet (see also Fig. 2). The two sections are identical in construction and both operate in unison on the one sheet at the same time. Each separating section comprises a substantially triangular plate 26 (Figs. 3, 5 and 6) pivotally mounted on a pin 27 supported in a block 28 secured to an angle iron 29 mounted on the front cross bar c, (see also Fig. 7).

Each plate 26 at the top is formed with a circular pocket 31 which is set off by a forward prong 32 and a rear prong 33. On the opposite side of the pivot the plate extends down as a tail section 34. The pocket 31 is so shaped as to provide a closely fitting seat for the lower edge of the wicket 16 at the loop 19 on that side, it being in alignment with the loop.

As the wicket reaches the separating device C the two plates 26 are in their clockwise positions as viewed in Fig. 3, the rear prong 33 being below the advancing wicket loop. The lower looped edge of the moving wicket therefore easily passes into the pockets of the two plates the front of the wicket striking against each front prong 32 of the associated plate in entering the pocket. The forward ends of the rails 24 where they are carried upon the front cross bar c terminate just short of the plates 26. Therefore a wicket when

it has moved off of the two rails 24 falls within the pockets 31 of the plates. This passing of a wicket from the rail into the triangular plate on each side of the machine is clearly shown in Fig. 3, the forward wicket which is entering the plate pocket having swung free of its restraining rail 24 on that side.

On receiving a wicket the two triangular plates begin rocking in a counterclockwise direction coming into the position shown in Fig. 4. Then the looped wicket edge is fully seated in the plate pocket. The chains 11 continue to advance the upper or inner edge of the wicket but the wicket at the bottom is confined entirely by the plates 26 and moves with the plates.

Both plates are moved together by connections with a common shaft. For this purpose the tail section 34 of each triangular plate is loosely connected to a slotted end 35 of a rod 36 located outside of its adjacent lower rail 24. The opposite end of each rod 36 is threaded in a pitman 37 and operates over a crank formed in a horizontal crank shaft 38. Shaft 38 extends across the machine and is journaled in bearings 41 formed in bearing blocks 42 secured to the transverse cross bar f. Rotation of shaft 38 will be described later.

Figure 4 illustrates an intermediate position in the rocking of the triangular plate 26 in its counterclockwise movement. When the plates 26 reach their furthermost oscillation, this being shown in Fig. 5, the wicket is released and swings forward. During this movement the front prong 32 of each plate moves into a position where it is below the lower edge of the wicket so that swinging of the wicket in clearing the triangular plates is unimpeded.

It will be observed that during this rocking action (Fig. 5) the next following wicket 16 is prevented from swinging forward as it engages the rear prongs 33 of the wicket separating device. Thus these two prongs act as stops in locating a wicket which has just cleared the ends of the rails 24.

The second mechanism which comes into operation incident to discharging the sheet now held in the separated wicket is a sheet lifting device D. This device is located in the front of the oven and in the path of travel of the sheet carried by the separated wicket just released from the separating device C. Device D is also in two sections one on each side of the machine. These two sections are identical in construction and both operate in unison on the sheet.

Each section of the sheet lifting device D comprises a lift arm 55 (Figs. 4, 5, 6 and 7) which at one end is keyed to a horizontal rock shaft 56. Shaft 56 extends across the machine and is journaled in brackets 57 bolted to the side frames 15. Both lift arms 55 of the two lifting devices D, being keyed to the shaft, thus operate in unison.

The free end of the lift arm 55 is wider and provides a sheet receiving shelf 58. When a wicket 16 with its sheet A has been released from the separating device C the sheet moves directly over the shelf 58 on each side of the machine. The arms 55 at such a time are in lowered position, this being the position shown in Fig. 5.

The shelf end 58 of the lift arm carries a pair of spaced upwardly extending ears 61 which form a guideway for a release finger 62. The release finger is cut through to provide an elongated slot 63, this being where the finger slides between

5

the ears 61. An oval extension 64 is formed on either side of the finger surrounding the slot 63 and presents a smooth slide surface on each side for working contact with the spaced ears. A bolt 65 extends between the two ears 61 and passes through the slot 63. This ties the ears together and at the same time prevents dislocation of the release finger, thus insuring only sliding movement between the lift and release members 55 and 62.

The release finger 62 thus extends over the top of its corresponding lift arm 55 and at the front is formed with a support foot 73 which is adapted to slide on the associated lift arm. When the released wicket 16 swings into the position of Fig. 5 its sheet engages against the two release fingers 62. The contacting faces of the support feet 73 are formed at an angle to the top of the fingers and this insures a flat engagement of the sheet. In this manner the release fingers definitely locate the sheet over the lift arm shelves 58.

Each release finger 62 is pivotally mounted on a pin 75 which is carried in a lateral extension 76 of a support sleeve 77. Sleeve 77 is loosely mounted on the rock shaft 56 between the lift arm 55 and the bracket 57 on that side. The pin 75 extends inwardly beyond the release finger, this being on the side opposite to the sleeve extension 76. This extended end of the pin is secured in one arm 78 of a bell crank lever 79. Lever 79 is loosely mounted on the rock shaft 56 alongside of the lift arm 55. This construction insures uniform and smooth movement of the bell crank lever 79 and the sleeve 77 which are held together by the pin 75 secured in the sleeve extension 76.

The other arm of the bell crank lever (indicated by the numeral 81) carries a pin 82 on which is mounted a cam roller 83. This roller operates against a peripheral cam 84 which is mounted on a horizontal cam shaft 85. Shaft 85 is located below and is parallel to the rock shaft 56. The shaft 85 extends across the machine and is journaled in bearings 86 (Fig. 6) formed in the side frames 15. For the purposes of the present invention shaft 85 will be considered the drive shaft for the sheet discharge mechanisms. This drive shaft is rotated in any suitable manner.

A spring 87 is secured at one end to an extension of the pin 82 and at the other end to the tie rod *a* (Fig. 7) of the supporting frame. This keeps the cam roller 83 against the periphery of the cam 84 so that during each revolution of the drive shaft the cam will rock the bell crank lever 79 and slide the release finger 62 relative to its associated lift finger 55.

Rocking of the shaft 56 lifts the lift fingers 55 to raise the bottom edge of the sheet resting within the wicket 16, to a position above the hooks 19. Thereupon the release fingers 62 slide forward, pushing the sheet off of the shelves 58 of the lift arms 55. Actuation of the rock shaft 56 for this lifting action and its connection with the cam and drive shaft 85 for sliding the release fingers 63 forward will now be described.

The drive shaft 85 (Figs. 1, 3, 6 and 7) carries at one end a drive sprocket 91. A drive chain 92 operates over the drive sprocket 91 and also passes over a sprocket 93 carried on one end of the crank shaft 38. The chain 92 also passes up and over a sprocket 94 which is keyed to one end of an upper horizontal shaft 95 (see also Fig. 2). Shaft 95 is a relatively short shaft and

6

rotates in a bearing 96 carried in one of the side frames 15.

From the sprocket 94 the chain 92 passes down and over an idler sprocket 97 loosely mounted on the rock shaft 56. A collar 98 is pinned on the end of the shaft 56 and keeps the idler sprocket in proper alignment on the shaft. In this manner both the wicket separating device C controlled from the crank shaft 38 and the sheet lifting device D operating from the rock shaft 56 and the drive shaft 85 are actuated in proper timed relation.

The shaft 95 at the top of the machine also carries an eccentric 101 (Figs. 1, 2 and 3). An eccentric strap 102 operates over the eccentric 101 and joins with the upper end of a connecting rod 103. The lower end of the rod is pivotally connected at 104 to a rocker arm 105. Arm 105 is mounted on the rock shaft 56 to which it is keyed. This arm is located between the sprocket 97 and the bearing bracket 57 on the adjacent side frame 15. By reason of this construction eccentric action between the parts 101, 102 lowers the lift fingers 55 to receive a sheet when it is carried into position by the wicket which has been released from the wicket separating device C.

The sheet A, upon reaching the position shown in Fig. 5 where it is directly above the shelves 58 of lift arms 55 and against the front faces of the support feet 73, comes within a pair of vertically disposed angle irons 111 (Figs. 3, 5 and 7). There is one angle iron on each side of the machine, the side leg of the angle being just outside of the widest sheet to be handled in the oven.

At the top each angle iron 111 is secured to the adjacent side frame 15 by a bolt 112 (Figs. 1, 2 and 3). Bolt 112 extends through a spacing sleeve 113 which locates the angle iron in proper position inwardly of the side frame.

Below this point of connection each angle iron 111 intermediate its length is secured to the adjacent side frame in a similar manner. For this purpose each angle iron carries a bracket 114 (see also Fig. 6) which is clamped against one end of a spacing sleeve 115 through which a stud 116 passes. At the other end the stud 116 extends through the bar *d* and is securely bolted against the bar *d*.

At the time a wicket 16 brings the sheet into the position of Fig. 5, the loop edge of the wicket is engaged by a catch device E which momentarily holds the wicket during the subsequent removal of the sheet therefrom. This prevents the wicket from swinging back at the time the sheet is being pushed off of the lift arm 55 by the release fingers 62. Catch device E is formed in two sections, one for each side of the machine.

Each section comprises a slotted supporting block 121 (Figs. 2, 3 and 7) which is mounted on and secured to the tie rod *a* by bolt 122. A catch finger 123 is pivoted on a pin 124 secured in the side walls of the slotted region of the block 121 and extending across the slot. The two catch fingers 123 are engaged by the wicket as the wicket moves toward the left (Fig. 3) in bringing the sheet into proper lifting position. A spring 125 is located in the bottom of the slot in the block 121 and presses upwardly against the catch finger tending to hold the finger in the path of the swinging wicket but allowing the wicket to snap past and then to be held in the position shown in Fig. 3, for a purpose which will be explained further.

With the wicket held against return movement, the release finger 62 on each side of the machine slides along the lift arm 55 associated therewith and pushes the sheet off of the arm. To assist in this removal a sheet bowing device F is utilized. This is best shown in Figs. 2, 3, 4 and 6 and again there are two identical sections of the device on opposite sides of the machine. This bowing device in addition to assisting in removal of the sheet from the lift fingers is instrumental in freeing a sheet from the wicket loops. It is of particular advantage where a wide sheet is used. Its action combines with the arm action to lift the sheet into a clear position relative to the wicket loop.

The bowing device comprises a curved sheet engaging and bowing fingers 135 which forms one arm of a bell crank lever 136. Each lever is pivoted at 137 on the angle iron 111 on its side of the machine. A slot 138 is cut in the angle iron to allow for clearance of the finger.

A slot 139 is cut in the bell crank lever 136 and a bolt 142 carried in the upper end of a connecting strap 143 extends through the slot. The slot allows for adjustment of the bolt to change the effective leverage for the bowing finger 135. When the desired amount of finger movement is obtained the bolt is tightened and this holds the position of the strap 143 on the bell crank lever. The lower end of the strap connects with a clevis 144 through which passes the bolt 65 carried in the lift finger lugs 61.

This construction insures rocking of the bowing finger 35 in synchronism with lifting of the arm 55. When the arm lifts the sheet the bowing finger moves from a position in back of the angle iron (Fig. 5) to a position first in engagement with the sheet (Fig. 4) and thence into the sheet bowing position shown in Fig. 3. If the sheet is narrow its top will not be held or if the effective leverage for the finger movement is lessened little or no bowing will take place. A wide sheet thus is bowed at the time of removal of the bottom of the sheet from the lift fingers 55. In this way not only the lower edge of the sheet is pushed off and away from the wicket but the middle part is forced away from the sustaining angle irons 111.

When the sheet is completely stripped off of the lift fingers it falls by gravity from the bottom ends of the angle irons and into a chute 145 (Figs. 2, 3 and 4). The upper part of this chute is secured to collars 146 which are carried on the tie rod a. In this manner the sheet after first being lifted above the edge of the loops 19 of the wicket 16 and while the wicket is being held by the catch finger 123, is discharged from the lift arm. In the case of a wide sheet this is at the same time that the sheet is bowed so that its vertical height is lessened sufficiently to entirely clear the wicket. It thereupon falls naturally into the discharge chute 145 from whence it may be carried away into a suitable place of deposit.

It is thought that the invention and many of its attendant advantages will be understood from the foregoing description, and it will be apparent that various changes may be made in the form, construction and arrangement of the parts without departing from the spirit and scope of the invention or sacrificing all of its material advantages, the form hereinbefore described being merely a preferred embodiment thereof.

I claim:

1. In an oven conveyor for transferring coated and lithographed sheets through a treating oper-

ation, the combination of a conveyor member having sheet carrying wickets for holding the sheets in separated position during transfer, said wickets having hooks thereon for engaging and supporting said sheets, and means located in the path of travel of the wickets for successively engaging the hook carrying portions of said wickets for forwardly spacing the foremost wicket from the succeeding wicket without disengaging the sheet from its associated hook and prior to discharging the sheet from the thus separated and forwardly spaced wicket.

2. In an oven conveyor for transferring coated and lithographed sheets through a treating operation, the combination of a conveyor member having sheet carrying wickets, hook elements carried by said wickets for engaging and supporting the sheets in separated position during transfer with one sheet in each wicket, means located in the path of travel of the wickets for successively engaging the hook element carrying portions of said wickets for forwardly spacing the foremost wicket from the adjacent succeeding wicket, and means for disengaging a sheet from a said forwardly displaced hook element to discharge the sheet from its separated wicket.

3. In an oven conveyor for transferring coated and lithographed sheets through a treating operation, the combination of a conveyor member having sheet carrying wickets, hook elements carried by said wickets for holding sheets in separated upright position during transfer, means for lifting a sheet to disengage it from its hook element, and means for engaging the elevated sheet and for displacing it from said lifting means.

4. In an oven conveyor for transferring coated and lithographed sheets through a treating operation, the combination of a conveyor member having sheet carrying wickets, hook elements carried by said wickets for holding sheets in separated upright position during transfer, devices located in the path of travel of the wickets for engaging and for progressively spacing each wicket from an adjacent wicket, means for lifting a sheet to disengage it from its hook element, and means for engaging and displacing the elevated sheet from said lifting means and from said separated wicket.

5. In an oven conveyor for transferring coated and lithographed sheets through a treating operation, the combination of a conveyor member having sheet carrying wickets for holding sheets in separated position during transfer, devices located in the path of travel of the wickets for engaging each wicket and for spacing it from an adjacent wicket while preventing more than one wicket separation at a time, means for removing a sheet from said separated wicket, and means actuated by said sheet removing means for engaging and bowing said sheet to assist in said removal.

6. In an oven conveyor for transferring coated and lithographed sheets through a treating operation, the combination of a conveyor member having sheet carrying wickets, devices located in the path of travel of the wickets for engaging a said wicket and for spacing it from an adjacent wicket, latch devices for holding the separated wicket in its spaced position, means for lifting a sheet relative to said latched wicket, and means for engaging and displacing the elevated sheet from said lifting means and from said separated wicket.

7. In an oven conveyor for transferring coated

and lithographed sheets through a treating operation, the combination of a conveyor member having sheet carrying wickets, devices located in the path of travel of the wickets for engaging a said wicket and for spacing it from an adjacent wicket, latch devices for holding the separated wicket in its spaced position, means for removing the sheet from said latched and separated wicket, and means actuated by said sheet removing means for engaging and bowing said sheet during its removal from the aforesaid segregated wicket.

8. In an oven conveyor for transferring coated and lithographed sheets through a treating operation, the combination of a conveyor member having sheet carrying wickets, hook elements carried by said wickets for holding sheets in separated position during transfer, devices located in the path of travel of the wickets for engaging a said wicket and for spacing it from an adjacent wicket, latch devices for holding the separated wicket in its spaced position, means for lifting a sheet to disengage it from its hook element, and release devices slideable on said lifting means for pushing off the raised sheet from said lifting means to discharge it from said separated wicket.

9. In an oven conveyor for transferring coated and lithographed sheets through a treating operation, the combination of a conveyor member having sheet carrying wickets, hook elements carried by said wickets for holding sheets in separated position during transfer, devices located in the path of travel of the wickets for engaging each wicket and for spacing it from an adjacent wicket, means for lifting a sheet to disengage it from its hook element, bowing fingers located above said lifting means for en-

gaging a said sheet, actuating means secured to said lifting means for moving said fingers to press against the middle section of the sheet to bow the same, means for changing the amount of movement of said bowing fingers by said actuating means to alter the amount of bow in the sheet, and devices for discharging the bowed sheet from said lifting means to remove it from its wicket.

10. In an oven conveyor for transferring coated and lithographed sheets through a treating operation, the combination of a conveyor member having sheet carrying wickets, hook elements located at the bottom of and carried by said wickets for holding sheets in separated position during transfer, oscillatory plates located in the path of travel of the wickets and having pockets for receiving each wicket and for separating it from an adjacent wicket, lift arms located below said separated wicket for engaging the lower edge of the sheet carried by the wicket to disengage said sheet from its hook element, release fingers mounted on said lift arms and movable therewith, and means for sliding said fingers along said lift arms to push the disengaged sheet off of the arms and clear of said wicket hooks to insure dropping of the sheet from said wicket.

ROY E. CUMMINGS.
